(57) CLAIM

The ornamental design for a pack, as shown and described.

DESCRIPTION

FIG. 1 is a perspective view of one embodiment of a pack of my new design in a first position.

FIG. 2 is a rear elevation view thereof.

FIG. 3 is a front elevation view thereof.

FIG. 4 is a right side elevation view thereof.

FIG. 5 is a left side elevation view thereof.

FIG. 6 is a top plan view thereof.

FIG. 7 is a bottom plan view thereof.

FIG. 8 is a perspective view of the pack of my new design in a second position.

FIG. 9 is a rear elevation view thereof.

FIG. 10 is a front elevation view thereof.

FIG. 11 is a right side elevation view thereof.

FIG. 12 is a left side elevation view thereof.

FIG. 13 is a top plan view thereof; and,

FIG. 14 is a bottom plan view thereof.

The broken lines in the figures are for the purpose of illustrating stitching and portions of the article and form no part of the claim.
